UNITED STATES PATENT OFFICE.

JAMES F. McELROY, OF ALBANY, NEW YORK; SUSIE HALE McELROY, EXECUTRIX OF SAID JAMES F. McELROY, DECEASED, ASSIGNOR TO CONSOLIDATED CAR-HEATING COMPANY, A CORPORATION OF WEST VIRGINIA.

DOOR-MOTOR.

1,145,908.

Specification of Letters Patent. Patented July 13, 1915.

Application filed June 1, 1911. Serial No. 630,680.

To all whom it may concern:

Be it known that I, JAMES F. McELROY, a citizen of the United States, residing at Albany, county of Albany, State of New York, 5 have invented certain new and useful Improvements in Door-Motors, the following being a full, clear, and exact disclosure of the one form of my invention which I at present deem preferable.

10 For a detailed description of the present form of my invention, reference may be had to the following specification and to the accompanying drawings, which illustrate my invention.

15 Figure 1 is a plan view and Fig. 2 a side elevation of my improved door motor; Fig. 3 is a plan of the same, together with the piping, and Fig. 4 is a side elevation of Fig. 3.

20 My present invention involves certain improvements in door motors based upon and constituting a development of my four-cylinder form of motor and relates particularly to the mode of supporting such a motor and 25 relating it to a car door to be operated thereby.

Turning to Fig. 1, A¹ and A² are two open-ended cylinders, facing each other but upon different levels, as more clearly appears 30 in Fig. 2. B¹ and B² are similar cylinders arranged parallel to and at one side of the cylinders A¹ and A² respectively. The latter are power cylinders, while B¹ and B² are cushioning or dash-pot cylinders, corresponding respectively to A¹ and A². A 35 cross-head D¹, connected to the piston rods a¹ and b¹ of the respective cylinders A¹ and B¹, travels on the set of cylinders A² and B¹, while a similar cross-head D², connected to 40 the piston rods a², travels on the cylinders A¹ and B². The two cross-heads D¹ and D² are connected by a rod C, so that the four piston rods and the two cross-heads all move together. The cylinder B¹ acts as a cushioning cylinder or dash-pot for the power cylinder A¹, and, similarly, the cylinder B² serves 45 as a cushioning cylinder or dash-pot for the power cylinder A². Thus if air is admitted to the right-hand closed end of the cylinder A¹ through the pipe 1, its piston rod a¹ will be forced to the left and at the same time the piston in cylinder B¹ will also move from the right-hand, open closed end of that cylinder toward the left-hand end and tend

to compress the air therein, which escapes, 55 however, through a restricted outlet. Conversely, if the air is admitted to the left-hand closed end of cylinder A² by the pipe 3, its piston rod a² will move to the right and the piston of B² will similarly move to the 60 right and provide the cushioning or damping effect upon the action of the cylinder A². On the cross-head D¹ are two ears d d which, as appears in Figs. 3 and 4, are connected to a movable element R through link d¹ and the 65 offset link R⁴. The above-mentioned cylinders are supported as clearly appears in Fig. 2. The standard S¹ at the left supports the left-hand ends of cylinders A² B¹ and also carries the lock hereinafter described. The 70 central standard S² carries the inner free ends of both sets of cylinders, while the standard S³ at the right carries the outer closed ends of the cylinders A¹ B².

The several cylinders are mounted in the 75 central standard S² in such a way as to be readily detachable therefrom. The cylinders, which are preferably of brass, are not screw threaded at the point where they enter the head of the standard S², but are merely 80 inserted in openings in the standard and are secured therein by screws s¹ s². These screws s¹ s² pass through the wall of the standard S² and the cylinders, so that after 85 the cylinders are inserted in the standard and the screws are in place they cannot be withdrawn. By merely removing the screws, however, the cylinders are left free to be withdrawn from their position in the standard. Since the end standards S¹ and S³ are 90 separate from the central one S², these end standards, together with the cylinders secured thereto, can thus be easily drawn away from the central standard. The open ends of the several cylinders are flared or beveled, 95 as clearly appears in dotted lines in Figs. 1 and 2. The piston rods are connected to their respective cross-heads D¹ and D² by means of sockets formed in the cross-heads, into which sockets the rods enter and abut 100 against the bottoms thereof. Cotter pins d² are then passed through the rods and through the projecting flanges around the edges of the sockets. These cotter pins are not essential, since the pressure of the pistons acts in every case to push the piston rod into its socket, but they are present as a 105 matter of precaution. This arrangement

renders it very easy to remove a piston and piston rod, since it only involves the withdrawing of the cotter pin and the moving aside of the cross-head, assuming that the 5 cross-head is first disconnected from the rod C, which joins the two cross-heads together and is connected thereto in a similar way.

In these figures G represents an air reservoir from which the air passes by pipe 2, 10 first through a strainer g¹, then through a stop cock g² to the inlet side of the controlling valve F, which it is not necessary to describe in detail, it being well understood that such a valve will act to admit the air to 15 either the cylinder A¹ by means of the pipe 1, or to the cylinder A² by means of the pipe 3. In the former case it will also connect the pipe 3 to the exhaust, while in the latter case it will also connect pipe 1 to the exhaust, so that when air is admitted to the 20 working end of one cylinder the working end of the opposite cylinder is connected to the exhaust. The exhaust pipe is shown at 5.

As stated above, the motor operates the 25 movable element R here shown as a door (see Figs. 3 and 4) by links d¹ and R⁴ and the door slides just inside the wall V of the car, being guided by the friction rollers r—r and arrested by the stop column V¹.

30 My motor being of a long, narrow form can be placed under the car seat at one side of the route of travel of the door and its stroke can be equal in length to the travel of the door from open to closed position. Hence 35 the cross-head D¹ can be connected directly to the door by links d¹, R⁴ which renders the installation extremely simple and compact, without the complication of devices for multiplying the range of stroke of the motor

40 to give an adequate range of travel of the door. The small diameter of cylinder will give the force required to move the door and also will occupy but little space transversely of the car. The advantage of this is that 45

the motor has a uniform leverage connection with the door at all points of the travel of the door, whereas the interposition of levers between the piston and door gives the piston a greater leverage as the door approaches its 50

closing position so that an arm, hand or leg caught in the door at that time may be crushed by the great force which the piston can exert through the leverage it has at that point. By applying the piston directly to 55

the door, as in my arrangement, it becomes easy to adjust its force, so that it can close the door without having sufficient power to crush or injure a person who may be caught between the door and the jamb. Such adjusted force becomes also no greater at the 60

door when the door is at either end of its route than at the middle. My arrangement is one producing such a uniform mechanical advantage of the motor upon the door, each 65 motor cylinder, for this purpose, being given

a stroke substantially equal to the length of the route traversed by the door and both cylinders being placed as nearly as possible in line with each other, the door-opening cylinder along and beside the route traveled 70 over by the door in opening, and the door-closing cylinder beyond the said route but in the same general line therewith. Moreover, the piston rod of the door-closing cylinder overlaps and is guided by the door-opening 75 cylinder, the thrust and buckling strain on the long rod of the remote door-closing cylinder being thereby taken up, and only the short door link d¹ interposed between the door and the point of push or thrust on the 80 motor which is the cross-head D¹. Likewise the door-opening cylinder has its closed end placed toward the door or adjacent to its rear edge and the thrust on its long piston rod, which overlaps and is guided by the 85 door-closing cylinder, is transmitted back by the rod C to the cross-head D¹ which is the point on the motor whence force is applied to the door through the short link d¹. In both cases the arrangement of the motor 90 with respect to the door is such that only a short and direct connection between them is required, although the motor stroke is very long and the thrust-strain on the piston rods would otherwise tend to buckle them. Also 95 the end of each piston rod is guided externally of the cylinder although the motor is applied to the lower part of the door where no piston guide extending across the closed position of the door or along the route of 100 travel of its forward edge would be permissible.

What I claim as new and desire to secure by Letters Patent is:

1. The combination with a movable element, of a motor cylinder, said cylinder being located along the route traveled by the movable element and having a stroke substantially equal to the travel of the movable element, a piston movable in said cylinder and provided with a piston rod, a guide external of the cylinder and movable thereon, said guide being connected to said piston rod, and a direct connection between said piston rod and the movable element. 110

2. The combination with a movable element, of a motor cylinder, said cylinder being located to one side of the route traveled by the movable element and having a stroke substantially equal to the travel of the movable element whereby the movable element and cylinder overlap at one extremity of the travel of said piston, a piston movable in said cylinder and provided with a piston rod, an external cross head guided by said cylinder and connected to said piston rod, and a direct connection between said cross-head and said movable element. 120

3. The combination with a movable element, of a motor cylinder, said cylinder be- 130

- ing located along the route traveled by the movable element and having a stroke substantially equal to the travel of the movable element, the closed end of said cylinder being located adjacent the rear edge of said movable element when the latter is in closed position, a piston movable in said cylinder and provided with a piston rod, a piston guide extending beyond said cylinder, a cross-head guided by said cylinder and connected with said piston rod, and a direct connection between said cross head and said movable element.
4. The combination with a movable element, of a motor cylinder having a stroke substantially equal to the travel of said movable element and located to one side of the route traveled by the rear edge of the latter with its closed end adjacent to said edge, a second cylinder extending beyond the one first named, a cross-head guided by the first cylinder and traveling the length of the same, and a connection between said cross-head and the respective pistons of both cylinders.
5. The combination with a movable element, of a cylinder for moving the same in one direction and having a stroke substantially equal to the travel of the rear edge of the said movable element and located to one side of the route of travel of the said rear edge, a cylinder for moving said movable element in the opposite direction and located between the first mentioned cylinder and the movable element but offset with respect thereto, an external cross-head guided by one of said cylinders, a connection between said cross-head and movable element, and a connection between said cross-head and the respective pistons of both cylinders.
6. The combination with a movable ele-
- ment, of cylinders for shifting the same in opposite direction and located in succession to one side of the route of the movable element in one of its extreme positions but offset with respect to each other, a piston and piston rod for each cylinder, a traveling cross-head guided by one cylinder, a connection from said cross head to the movable element, a traveling cross-head guided by the other cylinder, a connection between said cross head, a rod connecting the first mentioned cross head with the piston of the last mentioned cylinder, and a rod connecting the last mentioned cross-head with the piston of the other cylinder.
7. An apparatus of the character described comprising a reciprocating element to be operated, two power cylinders in facing relation but in different planes one of which cylinders overlaps the line of travel of the said element, pistons and piston rods for the respective cylinders, and offset connecting means for operating the said reciprocating element.
8. An apparatus of the character described comprising a reciprocating element to be operated, two power cylinders in facing relation but in different planes one of which overlaps the line of travel of said element, pistons and piston rods for the respective cylinders having a range of travel equal to the range of travel of said element, and offset connecting means for operating the said element.

In witness whereof I have hereunto set my hand, before two subscribing witnesses, this 29th day of May, 1911.

JAMES F. McELROY.
